FREDERIC C. WINKLER, OF LAKEWOOD, OHIO, ASSIGNOR TO WESTINGHOUSE ELECTRIC & MANUFACTURING COMPANY, OF EAST PITTSBURGH, PENNSYLVANIA, A CORPORATION OF PENNSYLVANIA

ILLUMINATING APPARATUS

Application filed October 28, 1932. Serial No. 640,175.

My invention relates, generally, to illuminating apparatus, and, more particularly, to reflectors of the type suitable for use in connection with flood lighting units.

The object of my invention generally stated is the provision of a reflector which shall be simple and efficient in operation and which may be economically manufactured.

A more specific object of my invention is to provide for causing a reflector to produce an evenly distributed projected beam of light.

Another object of my invention is to provide for eliminating filament striations in a specular reflector.

15 A further object of my invention is to provide for causing a reflector to produce an evenly distributed projected beam and a substantially perfect fade-out of the beam without filament striations by means of stippling on the reflecting or polished surface of the reflector.

20 A still further object of my invention is to provide a reflector having graduated symmetrical stiples on the inner or projecting portion and a large number of smaller symmetrical stiples unsymmetrically placed over the entire secondary reflecting or outer portion of the reflector.

25 Other objects of my invention will become apparent from a reading of the following description taken in conjunction with the accompanying drawing in which;

30 Figure 1 is a sectional view of a reflector showing a small portion of the stippling arranged in accordance with the invention, and

35 Fig. 2 is an enlarged view of a portion of the stippling shown in Fig. 1.

In reflectors of the type to which my invention relates, one of the most important features to be desired is to cause the reflector to produce an evenly distributed projected beam and a secondary beam having a substantially perfect fade-out.

40 I have discovered that these features may be obtained by the use of properly arranged stippling on the inner or reflecting surface of the reflector.

45 Another highly desirable feature in reflectors of this kind is to eliminate filament striations in the reflected beam caused by the re-

fection of the filament of the lamp or light source itself.

This feature is especially desirable where high wattage lamps are used which do not have a point source of filament.

55 Heretofore, filament striations have been eliminated by the use of a diffusing lens placed in front of the reflector or by imposing some sort of a diffuser directly upon the reflector or by using a frosted lamp.

60 I have discovered that the undesirable filament striations may be efficiently and inexpensively eliminated by the use of a graduated symmetrical stipple. Since the spread of the lamp filament is greatest at the points 65 on the reflector nearest to the lamp, the graduated stipple produces the desired even distribution of the projected beam.

65 In view of the fact that the diameter of the reflector increases from the back of the 70 reflector to the front or outer edge, the symmetrical arrangement of graduated stipples cannot be continued to the outer edge of the reflector because the stipples increase to such 75 large diameter as to produce a series of cone shaped bands around the entire periphery of the projected beam.

75 Since only a certain portion of the reflector, usually about sixty to seventy per cent of the back or inner portion, is utilized to 80 project the main beam the graduated symmetrical stipples may be formed in this portion only in order to produce an evenly distributed main beam.

85 The cone-shaped bands may be then eliminated and a substantially perfect fade-out produced by utilizing a different arrangement of stipples on the outer edge of the reflector which produces the secondary beam. The secondary beam is produced by the 90 remaining forty to twenty-five per cent of the reflecting surface on the outer end of the reflector.

95 The substantially perfect fade-out is produced by means of small symmetrical stipples placed unsymmetrically over the entire surface of the secondary reflecting portion of the reflector.

100 Referring now to the drawing, the reference character 1 designates, generally, a re-

reflector which may be used in connection with flood lighting units of various kinds such, for example, as window flood-lighting units and the like.

- 5 In the reflector shown the curvature of the reflecting surface is such that the main beam of light from the source (not shown) is accepted by approximately seventy percent of the reflector at the inner or back end, the 10 secondary beam being projected by approximately thirty percent of the reflector at the outer edge. In other words, the seventy per cent portion is covered by the graduated 15 symmetrical stippling 3 while the thirty per cent portion or outer band is covered with the small unsymmetrically positioned stip- 20 ples 5.

It will be readily understood that the ratio 25 of the area covered by the small unsymmetrical stippling 5 and the area covered by the larger graduated symmetrical stippling 3 may be varied to suit the size and shape or curvature of any particular reflector.

25 It is to be understood further that the small stippling 5 on the outer edge of the reflector may be also used with other than graduated symmetrical stippling on the main portion of the reflector and that the shape 30 of the stippling is immaterial.

30 From the foregoing description, it will be apparent that I have provided for obtaining substantially ideal conditions of light distribution from a single reflector thereby making it unnecessary to use a plurality of flood 35 lighting units to obtain an even distribution over a fairly large area. Furthermore, a plurality of units employing reflectors embodying the novel features of my invention 40 may be used to obtain a very even distribution over a large area since there is no tendency for the building up of intensity over certain areas because of the desirable fade 45 out distribution.

45 It may be stated, in conclusion, that while the illustrated example constitutes a practical and economical embodiment of my invention, I do not wish to limit myself strictly to the exact details herein illustrated, since 50 modifications of the same may be made without departing from the spirit of the invention, as defined in the appended claims.

I claim as my invention:

55 1. A light reflecting device comprising a concave member having an inner light reflecting surface formed with a plurality of protuberances thereon, said protuberances being distributed over the reflecting surface in such manner as to produce an even distribution of the projected main beam and a 60 secondary beam having a substantially perfect fade out.

65 2. A light projecting device comprising a concave member having an inner light reflecting surface with a plurality of protuberances formed thereon, the protuber-

ances on the outer or open end of the concave member being smaller in size than the protuberances on the remaining portion of the reflecting surface, thereby to provide substantially perfect fade out characteristics 70 of the projected beam.

3. A reflector for projecting a beam of light comprising a concave member with an inner reflecting surface provided with a band of small uniform stippling at the outer or open end thereof, the remaining portion of the reflecting surface being provided with large non-uniform stippling. 75

4. A reflector for projecting a beam of light comprising a concave member having an inner reflecting surface provided with stippling thereover, the stippling on the part of the reflecting surface utilized for projecting the main beam being symmetrical and graduated in size and the stippling on the part of the reflecting surface utilized to project the secondary beam being smaller than the largest of the symmetrical stippling, thereby to provide an even distribution of the main beam and a substantially perfect 80 fade out of the secondary beam.

5. A reflector for projecting a beam of light comprising a concave member having an inner reflecting surface with a plurality of protuberances formed thereon, the protuberances covering a predetermined portion of the reflecting surface being graduated in surface area, the protuberances covering the remaining reflecting surface being uniform in size and having a surface area which is less than the surface area of the protuberances over the said predetermined portion of the reflecting surface. 85 90 100

6. A reflector for projecting a beam of light comprising a concave member having an inner reflecting surface with a plurality of dome shaped protuberances formed thereon, the dome-shaped protuberances covering a predetermined portion the rear or back part of the reflecting surface being graduated in diameter in accordance with the increasing diameter of the reflecting surface, the protuberances over the remaining portion of the reflecting surface at the outer or open end of the reflector being uniform in diameter and of smaller diameter than any of the other protuberances. 105 110 115

7. A light reflector comprising a concave or hollow member having an interior reflecting surface with a plurality of rows of convexities therein gradually increasing in size from the back of the reflecting surface toward the front or open end of the reflector over a predetermined portion of the surface, the convexities covering the remaining portion of the reflecting surface near the open end of the reflector being of smaller size and uniform. 120 125 130

65 8. A light reflector comprising a concave or hollow member having an interior reflect-

ing surface provided with a plurality of circular rows of convexities thereover the convexities of each row over a predetermined portion of the reflecting surface at the back of 5 the reflector being graduated in diameter from the rear toward the edge or open end of the reflector, and the convexities over the

remaining portion of the reflecting surface being of uniform diameter.

In testimony whereof, I have hereunto subscribed my name this 20th day of October, 1932.

FREDERIC C. WINKLER.
